(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing the claimed design; and,

FIG. 2 is a front view of a display or portion thereof with graphical user interface showing the claimed design. The broken lines in the figures show a display screen or portion thereof, and form no part of the claimed design.

**1 Claim, 1 Drawing Sheet
(1 of 1 Drawing Sheet(s) Filed in Color)**

FIG. 1

FIG. 2

UNITED STATES PATENT AND TRADEMARK OFFICE
CERTIFICATE OF CORRECTION

PATENT NO. : D942,509 S
APPLICATION NO. : 29/738838
DATED : February 1, 2022
INVENTOR(S) : Dye et al.

Page 1 of 1

It is certified that error appears in the above-identified patent and that said Letters Patent is hereby corrected as shown below:

On the Title Page

In the Description, delete:

“FIG. 2 is a front view of a display or portion thereof with graphical user interface showing the claimed design.”

And insert:

--FIG. 2 is a front view of a display screen or portion thereof with graphical user interface showing the claimed design.--

Signed and Sealed this
Twenty-ninth Day of March, 2022

Drew Hirshfeld
